[57] CLAIM

The ornamental design for a lunch caddy, as shown and described.

DESCRIPTION

FIG. 1 is a top, side perspective view of a lunch caddy showing my new design;

FIG. 2 is a side elevational view thereof, the opposite side being the same;

FIG. 3 is a front elevational view thereof with the rear view being the same;

FIG. 4 is a top plan view thereof;

FIG. 5 is a bottom plan view thereof; and,

FIG. 6 is a cross-sectional view thereof taken along line 6—6 of FIG. 4.

The strap is removed from FIGS. 2–6 for ease of illustration.
